Primary Examiner — Clare E Heflin(74) *Attorney, Agent, or Firm* — Witters & Associates;
Steve Witters(57) **CLAIM**

The ornamental design for a street light, as shown and described.

DESCRIPTION

FIG. 1 is a perspective view of a street light showing the design thereof;

FIG. 2 is a bottom view thereof;

FIG. 3 is a side view thereof, wherein the other side view is symmetrical to this side view and is omitted for brevity;

FIG. 4 is a top view thereof;

FIG. 5 is a rear view; and,

FIG. 6 is a front view.

The broken lines shown on the drawings depict portions of the street light that form no part of the claimed design.
